UNITED STATES PATENT OFFICE.

EDMUND D. MOLONEY AND BERNARD A. MOLONEY, OF ROCHESTER, NEW YORK.

SHOE.

1,232,591.

Specification of Letters Patent. Patented July 10, 1917.

Application filed February 2, 1916. Serial No. 75,695.

To all whom it may concern:

Be it known that we, EDMUND D. MOLONEY and BERNARD A. MOLONEY, citizens of the United States, residing at Rochester, in the 5 county of Monroe and State of New York, have invented certain new and useful Improvements in Shoes, of which the following is a specification.

This invention relates to shoes, more particularly infants' shoes, and has for its object to provide, in a manner as hereinafter set forth, an outer sole for the complete shoe thereby increasing the life of the shoe and to further arrange, in a manner as herein- 10 after set forth, the outer sole with respect to the soft original sole of the shoe so that the outer sole will overlap said inner or soft original sole as well as overlapping the stitching between the upper and soft sole 15 under such conditions reducing the ripping off of the original or inner sole when in use.

Further objects of the invention are to provide a shoe for infants' use which is simple in its construction, durable, inexpensive, 20 to manufacture and possessing an increasing 25 lasting quality over the ordinary soft sole infant's shoe now in general use.

With the foregoing and other objects in view the invention consists of the novel construction, combination and arrangement of parts as hereinafter more specifically described and illustrated in the accompanying drawings, wherein is shown an embodiment of the invention but it is to be understood 30 that changes, variations and modifications 35 can be resorted to which come within the scope of the claim hereunto appended.

In the drawings wherein like reference characters denote corresponding parts 40 throughout the several views:

Figure 1 is an elevation of an infant's shoe in accordance with this invention, the outer shoe being partly disconnected.

Fig. 2 is an elevation of an infant's shoe 45 in accordance with this invention.

Fig. 3 is a longitudinal sectional view of the outer sole.

Fig. 4 is a section across the fore part of the shoe.

Referring to the drawings in detail 1 de- 50 notes the ordinary soft sole infant's shoe now in general use and 2 denotes the soft sole thereof. As is well known, the process or method of manufacturing infants' soft sole shoes, is the stitching of the marginal 55 portion of the bottom of a complete upper, when turned wrong side out, to the marginal portion throughout of an inturned soft sole, after which the upper and sole are turned right side out. 60

The reference character 3 indicates the outer sole which may be of any suitable material, preferably sole leather, and which is secured throughout to the sole 2. The sole 3 65 may be secured to the sole 1 in any manner, 70 preferably by a suitable adhesive.

What we claim is:—

As a new article of manufacture an infant's shoe of the non-lasted type comprising 70 an upper, an inturned soft leather sole, said upper having a portion of its outer face in- 75 turned and stitched to the marginal portion throughout of the inturned surface of said sole whereby the upper is secured to the sole, and a leather sole for tread purposes having 75 its upper face cemented throughout to the outer face of the first mentioned sole whereby the first mentioned sole is permanently secured to the second mentioned sole for 80 tread purposes.

In testimony whereof we affix our signatures in the presence of two witnesses.

EDMUND D. MOLONEY.
BERNARD A. MOLONEY.
